UNITED STATES PATENT OFFICE.

MAX LANGER, OF HERMSDORF, NEAR BERLIN, GERMANY, ASSIGNOR TO AUTOMATIC ELECTRIC COMPANY, OF CHICAGO, ILLINOIS.

TELEPHONE SYSTEM.

Application filed August 29, 1921. Serial No. 496,335.

(GRANTED UNDER THE PROVISIONS OF THE ACT OF MARCH 3, 1921, 41 STAT. L., 1313.)

To all whom it may concern:

Be it known that I, MAX LANGER, a German citizen, and a resident of Hermisdorf, bei Berlin, Röderstrasse 58, Germany, have invented certain new and useful Improvements in Telephone Systems (for which I have filed application in Germany, application No. S 53922 VIII/21^a, dated August 10, 1920), of which the following 10 is a specification.

This invention relates in general to circuit arrangements for a two wire junction leading from an automatic exchange to another exchange in which the testing for 15 engagement is effected over only one of the two wires. A feature of the arrangement is that in addition to the blocking means at the outgoing end of the line, blocking means is also provided at the other end 20 under the control of connecting arrangements at this end, which prevent the line being taken into use when the line is out of order or closed for service. The blocking means at the incoming end of the line 25 controls the testing arrangement at the other end over the test lead.

According to the present invention switching means are provided for connecting at the incoming end of the test lead of 30 the trunk line potential that differs from the blocking potential provided at that end of the line, thereby setting in action the metering arrangement at the outgoing end of the test lead. The trunk lead used for testing can thus be used not only for controlling 35 the testing arrangement by means of the blocking means at the incoming end of the line, but also for additional switching processes, such as the metering and release of a 40 connection. Preferably the meter potential is connected to the test lead either after the connection has been completely set up or at the end of the conversation.

Furthermore the invention enables the 45 selecting device to be released directly by the metering potential through the registering arrangement by means of one of the slow acting devices so that the releasing process is effected over the test lead in the 50 direction from the outgoing end to the incoming end.

The drawing shows diagrammatically an example of carrying out the invention. The

contacts are given reference numbers and also small letters which indicate the windings marked in capital letters by which they are operated; thus the double wound relay A has armature contact 34.

When the receiver is lifted at the substation T_a the preselector is set in known 60 manner on a free first selector I GW. The relays T and C are operated from earthed battery, contact 1, windings I and II of the relay T, test arm of the preselector VW, winding I of the slow acting relay C, off 65 normal contact k₁, earth.

The relay T short circuits at contact 2 the circuit of its high resistance winding I and switches the subscriber's line through to the first selector I GW at contacts 3 and 70 4. At the first selector I GW the relay A is operated and closes a circuit from earthed battery, winding II of the slow acting relay C, winding I of the slow acting relay V, contacts 5, 6, earth. The operation of slow 75 acting relay V opens at contacts 7 the circuit of the release magnet M. The contact 8 is closed but the contact 9 controlled by relay A is opened; hence the slow acting relay W is not operated. At each train of 80 number impulses the relay W is however energized and serves then as a switching relay for the first selector I GW, the second selector II GW and the connector LW. The slow acting relay C opens contact 10 and 85 closes 11, thereby the meter relay ZR is disconnected at the first selector I GW from the trunk line. The first selector I GW is now set on a free trunk line VL, which has the off normal contact k₃ closed. When the 90 free trunk line VL is reached, the following test circuit is closed: earthed battery FP, off normal contact k₃, b-lead of the trunk line VL, contacts 12, 13, winding I of the relay F, test arm of the first selector I GW, 95 winding II of the test relay P, contact 14, winding I of the test relay P, earth. The test relay P is operated in this circuit and short circuits at 15 its high resistance winding I, thereby the b-lead of the trunk line is 100 blocked at the outgoing end. The relay F is at first not operated owing to the differential effect of its windings II and III. The subscribers' lines are connected through at contact 16, 17, to the free trunk line. 105 Furthermore the circuit of the release mag-

net M is opened at contact 18. At the first number impulse which operates the second selector II GW, the relay W is energized over contacts 8 and 9, while the winding I of the relay E is energized in a circuit from earthed battery, relay A₁, contact 118, trunk lead *a*, winding I of the relay E, contacts 16, 33 and 34, earth. Thereby the contacts 19 and 20 are closed and 21 opened. The relay 10 E locks itself in series with the windings II and III of the relay F. The *b*-lead of the trunk line is switched through at contact 20, thereby the test relay P is disconnected from the *b*-lead and the windings II and III 15 of the relay F are energized. Winding I of the relay F no longer receives any current. By the energization of relay F, the contact 22 is closed, and thereby the winding I of the relay E is short circuited. At the 20 first lifting step of the second selector II GW the off normal contact *k*₃ is operated, thereby the relay B₁ at the second selector II GW is energized in a circuit from earthed battery, resistance *v*₃, contacts 31, 11, 17, 20, 25 *b*-lead of the trunk line, off normal contact *k*₂, contact 23, windings I and II of the relay B₁, earth. The relay B₁ at 23 removes the short circuit from the winding I of the relay C₁ and closes contact 24. The relay C₁, 30 however, is not energized because it does not receive enough current. The second selector II GW sets itself on a free connector. When the second selector reaches the free connector LW a test circuit is closed from earthed battery, relay C₂, winding I of the 35 test relay P₁, contact 25, winding II of the relay P₁, earth.

The test relay P₁ is operated over this 40 circuit and short circuits at contact 26, its high resistance winding II. It therefore at 27 and 28 switches the trunk leads *a* and *b* through to the connector LW and opens the contact 29 in the circuit of the release magnet M₁. By the operation of relay C₂ the 45 contact 30 in the circuit of the release magnet M₂ of the connector LW is opened. During the transmission of number impulses 50 for setting the connector LW, the slow acting relay W is again energized, and the contact 31 is thereby closed. The relay B₂ at the connector is now energized in the circuit from earthed battery, resistance *v*₃, contacts 31, 11, 17, 20, trunk lead *b*, off normal contact *k*₁, winding I of the relay C, contact 55 28, relay B₂, earth. Likewise during the train of impulses for the connector LW, the relay A₂ is energized in a circuit from earthed battery, relay A₂, contacts 32, 27, trunk lead *a*, contacts 22, 16, 33, 34, earth. 60 When the connection has been completed in known manner to the wanted subscriber and when the latter has answered the relay Y at the connector is energized and closes contact 35. Thereby the relay Q is energized 65 in a circuit from earthed battery, off normal

contact *k*₄, relay Q, contact 35, earth. The relay Q locks itself over contact 36 till the release of the connector LW. The relay Q furthermore closes the contacts 37, 38, which for the present effect no circuit changes 70 because the contact 39 of the relay Y is opened.

When at the end of the conversation the calling subscriber Ta hangs up his receiver the relay A at the first selector I GW is 75 deenergized, hence current no longer flows through the winding I of the slow acting relay V, and the winding II of the slow acting relay C. The relay C is so arranged that it releases its armature a little quicker 80 than the slow acting relay V. Hence the slow acting relay V remains energized over its winding II and the *a*-lead of the trunk line VL in a circuit from earthed battery, 85 winding II of the slow acting relay V, contacts 40, 41, 16, 22, trunk lead-*a*, contacts 27, 37, resistance *v*₄, earth. When relay C is deenergized it closes the contact 10 and thereby connects the meter relay ZR to the *b*-lead. This meter relay ZR, however, is only energized when the wanted subscriber 90 hangs up his receiver, since the relay Y at the connector LW is then deenergized and closes contact 39 so that current passes from earthed battery ZP, contacts 39, 38, 28, 95 winding I of the relay C₁, off normal contact *k*₃, *b*-lead of the trunk line VL, contacts 20, 17, 10, meter relay ZR, earth. Through the energization of the meter relay ZR the contact 42 is closed, and thereby the circuit of meter Z is closed, so that the metering is effected. Simultaneously with the energization of the meter relay ZR, the contact 40 is opened and thereby the winding 100 II of the slow acting relay V is deenergized. The deenergization of the slow acting relay V causes the contact 43 to be closed and thereby the winding II of the relay P is short circuited. The relay P releases its 105 armature so that at contact 18 the following release circuit is completed: earthed battery, off normal contact *k*₅, release magnet M, contacts 18, 7, earth. Thereby the release magnet M is energized and the first selector I GW is released. The opening of contact 110 17 breaks the circuit of relay ZR which opens contact 42. The energized release magnet M, at contact 46 opens the circuit of the relay T at the pre-selector, so that the latter is also rendered free. The release of relay P causes the deenergization 115 of windings II and III of the relay F and of the winding II of the relay E. The relays E and F are so arranged that the relay E releases its armature quicker than the relay F, hence the winding II of the relay F is short circuited at 21 after the relay E has been deenergized. The release of relay E also disconnects at 20 the *b*-lead of the 120 trunk line VL, so that an increased cur- 125

rent flows over the winding III of the relay F and the relay C₁, from earthed battery, winding III of the relay F, contacts 21, 44, 12, off normal contact k₃, winding I of the 5 relay C₁, windings I and II of the relay B₁, earth SP. The relay C₁ is now energized. The operation of relays C₁ and B₁ effect the short circuit of winding I of the relay P₁. The relay P₁ is therefore de- 10 energized and thereby energizes the magnet M₁ in the following circuit: earthed battery, off normal contact k₆, release magnet M, contacts 45, 29, earth. The second selector II GW is thereupon released. Fur- 15 thermore the actuation of the off normal contacts k₃ causes the free potential FP to be again connected to the trunk line. Sub- sequent to the release of the relay P₁, the relay C₂ at the connector is deenergized. 20 Thereby the contact 30 is closed and release magnet M₂ is therefore energized in the circuit, earthed battery, off normal contact k₇, release magnet M₂, contact 30, earth. Thus the connector LW is disconnected. 25 When the calling subscriber Ta hangs up his receiver after the trunk line VL has been taken into use and before a train of impulses over the second selector II GW has been transmitted, then the relay A at 30 the first selector I GW is released and also the relay V because the earth potential at the resistance v₄ is missing at the a-lead of the trunk line VL. The release of the slow acting relay V short circuits the relay 35 P so that this releases its armatures. Hence the contacts 7 and 18 are closed and thus the release magnet M of the first selector I GW is connected up. By the release of relay C its contact 10 connects up the meter 40 relay ZR to the b-lead of the trunk line. However, the relay E is not energized till the transmission of the first number im- pulse that operates the second selector II GW and according to the abovementioned 45 assumption has not yet been operated, there- fore the b-lead of the trunk line VL has not yet been switched through at 20. Hence the meter relay ZR receives no current from the meter battery ZP. The meter Z is there- 50 fore not operated although the disengaged potential FP is equal to the meter poten- tial ZP.

Having now described my invention what I consider to be new and desire to have pro- 55 tected by Letters Patent will be pointed out in the following claims.

What I claim as my invention is:

1. In a telephone system, means including a train of automatic progressively movable 60 switches for connecting a calling and a called line, means in the final switch for connecting a source of current to one of the talking conductors when the conversation is over with, said means being responsive only 65 to the replacement of the receiver on the

called line, a measured service device for the calling line, a controlling relay for said device, and means responsive only to the replacement of the receiver on the calling line for connecting said controlling relay to 70 said talking conductor to render such relay responsive to said current source.

2. In a telephone system, means includ- 75 ing a train of automatic progressively mov- able switches for connecting a calling and a called line, means in the final switch for connecting a source of current to one of the talking conductors when the talking connec- 80 tion is broken, a measured service device for the calling line, a controlling relay for said device responsive to said current source, and release mechanism in said switches also re- sponsive to said current source.

3. In a telephone system, means includ- 85 ing a train of automatic progressively mov- able switches for connecting a calling and a called line, means in the final switch for connecting a source of current to one of the talking conductors when the talking connec- 90 tion is broken, a measured service device for the calling line, a relay in the first of said switches, means in said switch controlled over circuits excluding the succeeding switches for connecting said relay to said talking conductor to render the same re- 95 sponsive to said current source, and a circuit over which said relay controls the said meter.

4. In a telephone system, a two conductor 100 trunk line connecting two exchanges, a meter controlling relay in the first exchange, a two motion switch in the second exchange having a change over control relay, means in the first exchange for connecting a source of current to a conductor of said trunk during 105 the setting up of a connection to operate said change over control relay, and means in the second exchange for connecting another source of current to said conductor for operating said meter controlling relay. 110

5. In a telephone system, a two conductor 115 trunk line connecting two exchanges, a meter controlling relay in the first exchange, a two motion automatic switch in the second exchange having a change over control re- 120 lay, means in the first exchange for connect- ing a source of current to a talking conductor of said trunk during the setting up of a connection to operate said change over control relay, and means in the second ex- change controlled by the called subscriber for connecting another source of current to said conductor for operating said meter con- 125 trolling relay.

6. In a telephone system, two exchanges, 125 a two conductor trunk line connecting said exchanges, means including an automatic switch in each exchange for setting up a talking connection over said trunk line, the switch in the second exchange being con- 130

trolled by a plurality of series of impulses transmitted over one conductor of said trunk line, change-over means for said switch controlled over the second conductor of said trunk line, a measured service device associated with the calling line, and a controlling relay for said device controlled over said second conductor also.

7. In a telephone system, a trunk line connecting two exchanges, an automatic switch in the first exchange for seizing said trunk line, a meter control relay and a test relay in said switch, a source of current in the second exchange for supplying current to said relays, said source being normally connected to a talking conductor of said trunk line, means for disconnecting said source after testing, and means for again connecting it for metering, contacts normally con-

necting said talking conductor with said test relay, and means for shifting the said conductor into connection with said meter control relay after said source is first disconnected and before it is again connected. 20

8. In a telephone system, a trunk line having but two conductors, said trunk line connecting two exchanges, a meter controlling relay in the first exchange, a two motion switch in the second exchange having a change over control relay, means in the first exchange for connecting a source of current to a conductor of said trunk during the setting up of a connection to operate said change over control relay, and means in the second exchange for connecting another source of current to said conductor for operating said meter controlling relay. 25 30 35

MAX LANGER.
